JOHN EARNEST SAGE AND NELS VALDEMAR BORGESON, OF THE PROVINCE OF RIZAL,
PHILIPPINE ISLANDS.

SANITARY COMB.

1,241,286.

Specification of Letters Patent. Patented Sept. 25, 1917.

Application filed April 26, 1917. Serial No. 164,687.

To all whom it may concern:

Be it known that we, JOHN EARNEST SAGE and NELS VALDEMAR BORGESON, citizens of the United States, and residents of the 5 Province of Rizal, Philippine Islands, have invented a certain new and useful Improvement in Sanitary Combs, of which the following is a specification.

One of the principal objects of our invention 10 is to provide an improved comb, having means for housing the comb when not in use and for cleaning the comb teeth, and also having means for protecting the comb teeth against damage when the comb is in 15 closed position.

A further object of the invention is to 20 provide an improved comb of the class described, which will be characterized by advantages of simplicity, durability, efficiency in operation, and economy in manufacture.

With these and other objects in view which will become apparent as the description proceeds, the invention resides in the 25 construction, combination, and arrangement of parts hereinafter more fully described and claimed, and illustrated in the accompanying drawing, in which like characters of reference indicate like parts throughout the several figures, of which—

30 Figure 1 represents a view in perspective of the comb showing the same in closed position;

Fig. 2 represents a similar view showing the comb in open position ready for use;

35 Fig. 3 represents an end elevational view of a comb in closed position;

Fig. 4 represents a view in section taken transversely on the plane indicated by the line 4—4 of Fig. 1;

40 Fig. 5 represents a view in section taken transversely on the plane indicated by the line 5—5 of Fig. 2;

Fig. 6 represents a fragmentary view in perspective showing the comb in open position, the guard being shown in an intermediate position for clearness of illustration;

45 Fig. 7 represents an enlarged fragmentary plan view of one edge of the casing showing the perforations therein through which the comb teeth extend.

Referring more particularly to the drawing, the comb includes the metallic back 5 and the metallic teeth 6 carried thereby.

55 It is to be understood that the comb proper,

as well as the other parts of the device, may be made of any suitable material. Over the back 5 a casing 7 is adapted to slide transversely, and this casing is in the form of a flattened tube, open at each end. One 60 edge of the casing is provided with a plurality of perforations 8 through which the comb teeth 6 extend. These perforations are of a size to snugly fit the comb teeth, so that foreign matter cannot enter the cas- 65 ing through the perforations.

The width of the casing 7 is such that when it is moved into position for inclosing the teeth 6 as shown in Fig. 4, the outer ends of the teeth will be flush with the outer 70 edge of the casing.

The ends of the comb back 5 are substantially flush with the ends of the casing 7, and each carries a pin 9 extending through a slot 10 provided longitudinally in what 75 may be termed the inner end of a link 11. Collars 12 secured on pins 9 outside of the links 11, prevent accidental detachment of said links from the pins. These links 11 conform in shape to the ends of the casing 80 7, and at their other ends the links are fixedly connected to a substantially U-shaped guard 13. When the comb is in closed position, as indicated in Fig. 1, the guard 13 fits over the edge of the casing 7 through 85 which the comb teeth extend. When the comb is in open position, however, as indicated in Fig. 2, the guard 13 fits over the opposite edge of the casing.

The comb being closed and in the position 90 indicated in Fig. 1, and it being desired to open the comb for use, the casing 7 is grasped in one hand, and the guard 13 is grasped by the fingers of the other hand and pulled downwardly. This will shift the 95 links 11 over the pins 9 until the pins occur in the outer ends of the slots 10, and a further pull will move the comb back 5 laterally through the casing 7, thus exposing the comb teeth 6. The guard 13 may 100 then be swung around, as indicated in Fig. 3, until it is positioned over the edge of the casing opposite that through which the comb teeth extend. Then the guard may be pressed downwardly to engage the edge of 105 the casing, as indicated in Figs. 2 and 5. The comb is then ready for use.

When it is desired to close the comb, the guard 13 is first grasped and lifted slightly to disengage the casing 7, this movement 110

being allowed by the lost motion of the pin and slot connection between the links and the comb back. A continued pull on the guard away from the casing 7 will shift 5 the comb laterally through the casing in an opposite direction from the position indicated in Fig. 5, to that indicated in Fig. 4, thus withdrawing the comb teeth 6 through the perforations in the casing 7, and this 10 operation it will be noted will serve to clean the teeth and strip them of any dirt which may have adhered to the teeth during the use of the comb.

The teeth having been withdrawn within 15 the casing 7, the guard is then swung around on its pivot to a position opposite the edge of the casing through which the teeth extend, and then the guard is pressed into position against the casing to close the openings 8 against any possible entrance of dirt or dust.

It will thus be seen that the comb will be automatically cleaned during the process of closing the comb, and that it will be always 25 retained in a sanitary condition and protected from damage. One of the commendable features of the invention is the fact that, when the comb is closed, it may readily be slipped into one's pocket without risk 30 of tearing or abrading the material.

Although we have described the preferred embodiment of our invention, we may desire to make such changes in the construction, combination, and arrangement of parts 35 thereof, as do not depart from the spirit of the invention and the scope of the appended claims.

We claim:

1. The combination with a comb, of a flattened open-ended tubular casing of a width 40 substantially equal to the width of the comb in which casing the comb back is contained, said casing being slidable laterally over the back and having at one end a plurality of 45 perforations through which the comb teeth slidably extend, pins projecting longitudinally from the ends of the comb back, links having slots at one end through which the

pins extend, a substantially U-shaped guard fixedly secured to the opposite ends of the 50 links, said links being of a shape and dimensions conforming substantially to the cross sectional shape and dimensions of the said casing.

2. The combination with a comb, of a flattened open-ended tubular casing of a width substantially equal to the width of the comb, and in which the comb back is contained, said casing being slidable laterally over the comb back and being provided at one edge with 60 a plurality of perforations through which the comb teeth slidably extend, a guard of a substantial U-shape adapted to fit on one edge or the other of the casing, links fixedly connected at one end to the ends of the 65 guard, and pin and slot connections between the opposite ends of the links and the comb back, substantially as described.

3. The combination with a comb, of a casing in which the comb is contained, said 70 casing being provided with perforations through which the comb teeth slidably extend, and a guard arranged parallel with the comb back and having a lost motion connection with the comb back whereby the 75 guard may move toward and away from the comb back, said guard being adapted when the comb is in closed position to be moved into position for closing the perforations provided in the casing. 80

4. The combination with a comb, of a casing through which the comb is laterally slidable, said casing being provided with openings through which the comb teeth slidably extend, and a guard having a pivotal and lost motion connection with the comb and adapted when the comb is withdrawn into the casing to be moved into position for closing the perforations in the casing. 85
